DENTAL CHAIR OR SIMILAR ARTICLE

Sanford S. Golden, West Los Angeles, Calif.

Application April 10, 1956, Serial No. 40,998

Term of patent 14 years

(Cl. D15—3)

FIG. 1.

FIG. 2.

FIG. 3.

Fig. 1 is a perspective view of a dental chair showing my new design, the dental chair being viewed from the left side and rear and being in an upright and elevated position;

Fig. 2 is another perspective view thereof, the dental chair being viewed from the right side and front and being in an inclined and lowered position; and

Fig. 3 is still another perspective view thereof, taken as indicated by the arrow 3 of Fig. 2.

I claim:

The ornamental design for a dental chair or similar article, substantially as shown.
